CLAIM

The ornamental design for an element of a shoe midsole, as shown and described.

DESCRIPTION

FIG. 1 is a side elevational view of an element of shoe midsole showing my new design;

FIG. 2 is a cross-sectional view taken along the line 2—2 of FIG. 1; and,

FIG. 3 is a cross-sectional view taken along the line 3—3 of FIG. 1.

The broken line showing of a shoe in FIGS. 1-3 is for illustrative purposes only and forms no part of the claimed design.
